UNITED STATES PATENT OFFICE.

FRANK B. COOK, OF CHICAGO, ILLINOIS.

ELECTRIC SIGN APPARATUS.

No. 839,455.

Specification of Letters Patent.

Patented Dec. 25, 1906.

Application filed January 30, 1904. Serial No. 191,302.

To all whom it may concern:

Be it known that I, FRANK B. COOK, a citizen of the United States of America, and a resident of Chicago, Cook county, Illinois, have invented a certain new and useful Improvement in Electric Sign Apparatus, of which the following is a specification.

My invention relates to electric apparatus of the character described in my application, Serial No. 164,184, filed July 3, 1903, and is more particularly adapted for use in connection with electric signs. In said former application I have claimed my invention broadly, while in the present application I have claimed both broadly and specifically the features which constitute matters of improvement on the broad idea of employing one or more self-contained electrothermal switches for automatically controlling the incandescent lamps of an electric sign and for automatically causing said lamps or groups of said lamps to flash or glow in the ordinary and well-known manner or for controlling any other suitable or desired translating means.

Generally stated, the object of my present invention is to provide an improved construction and circuit arrangement of electrothermal switches whereby a plurality of lamps or a plurality of groups of lamps may be caused to automatically and successively glow, and also whereby a plurality of lamps or a plurality of groups of lamps may be caused to flash or glow successively and then to all glow simultaneously.

A special object is to provide an improved construction and arrangement whereby a plurality of electrothermal switches may be employed for controlling the lamps and whereby the thermal or heat-generating circuit of one switch may be controlled by the switch-contacts of another switch.

It is also an object to provide certain details of improvement tending to increase the general efficiency and serviceability of electric sign apparatus of this particular character.

To the foregoing and other useful ends my invention consists in matters hereinafter set forth and claimed.

In the accompanying drawings, Figure 1 is a diagram illustrating a construction and circuit arrangement whereby a plurality of lamps or a plurality of groups of lamps may be caused to glow successively. Fig. 2 is a similar diagram illustrating a matter of further improvement, whereby the lamps or the groups of lamps may not only be caused to

glow successively, but whereby the successive glowing of the lamps may be followed instantly by a simultaneous glowing of the same.

As thus illustrated and referring to Fig. 1, my improved electric sign apparatus may comprise a plurality of incandescent lamps 1, 2, 3, and 4 or may comprise a plurality of groups of lamps—such, for example, as a sign in which each group of lamps constitutes either a letter or a word or even a complete sentence. For convenience of illustration and description, however, it will be sufficient in the present case to consider merely a plurality of individual incandescent lamps adapted to glow in succession, as illustrated. If desired, both the electrothermal switches and the lamps may be operated from a common source of current—such, for example, as an ordinary dynamo or generator A. The usual and well-known parallel arrangement of the lamps can of course be adopted in any suitable known or approved way. The electrothermal switches B, C, and D are in a general way similar to each other, each, as illustrated, consisting of a hollow body and having its interior divided by a thin flexible diaphragm and provided with switch-contacts adapted to be opened and closed by the vibrations of said diaphragm, and also with a heating-coil or other suitable resistance inclosed within or associated with one of the chambers at each side of said diaphragm. For example, the electrothermal switch B comprises a casing b, provided interiorly with a dividing-wall or flexible diaphragm b', and provided at its ends with caps b² and b³. The interior thus hermetically sealed is divided into two compartments, one of which compartments comprises the heating-coil or resistance b⁴. The said coil connects at one end with a binding-post or terminal b⁵ and at the other end with a contact b⁶, which latter is normally in engagement with the said diaphragm. Another contact b⁷ is provided and arranged in such a manner as to be normally out of engagement with the said diaphragm. When sufficient current passes through the said heating-coil, heat is generated and the air in the compartment in which the coil is inclosed expands and moves the diaphragm out of engagement with one contact and into engagement with the other contact. This same principle of construction is embodied in the other switches. The principle of construction of the apparatus, together with the slight vari-

ation in the construction in the different switches, will, however, be best understood by considering the operation of the apparatus.

Assuming the apparatus to be in the condition shown in Fig. 1, current passes over the generator A, through the conductor 5, to and through the lamp 1, through the conductor 6, to the binding-post *d* of the switch D, the contact *d*' being carried by the diaphragm *d*³, while the contact *d*² is carried by the casing *d*⁴. The circuit is then continued through the binding-post *d*⁵ and through the conductor 7 to the binding-post *e* of the switch C and through the normally closed contacts *c*' and *c*², the contact *c*' being carried by the diaphragm *c*³, while the contact *c*² is carried by the casing *c*⁴. The circuit is then continued through the binding-post *c*⁶ and the conductor 8 to the binding-post *b*⁵, thence through the heating-coil *b*⁴, through the contact *b*⁶ and the diaphragm *b*⁷, through the binding-post *b*⁸, and thence through the conductors 9 and 10 to said generator or other source of current A. The current from the source of supply and the resistance of the circuit thus formed are of such character as to insure a normal flow of current sufficient to generate considerable heat in the coil *b*⁴ and to of course cause the lamp 1 to glow. The heat generated in the chamber *b*⁹ of the switch B expands the air in such chamber, and thereby causes the diaphragm *b*⁷ to move out of engagement with the contact *b*⁶ and into engagement with the contact *b*⁸. The diaphragm itself, it will be seen, in this way constitutes two of the circuit-contacts, the opening of the contacts included in the thermal or heating circuit of the switch B causing the lamp 1 to cease glowing and a practically instantaneous closing of the contacts, including the contact *b*⁸, serving to close a circuit through the lamp 2. This automatically-closed circuit is from the generator A through the conductor 5, thence through the conductors 11 and 12, through the binding-post *c*⁹ of the switch C, through the contact *c*', carried by the diaphragm *c*³, thence through the contact *c*⁸, with which one end of the coil *c*⁹ is connected, thence through the said coil and the binding-post *c*¹⁰, through the conductor 13, through the lamp 2 and the conductor 14, thence through the binding-post *b*¹⁰ and the contact 7, through the diaphragm *b*⁷ and the binding-post *b*⁸, and thence through the conductors 9 and 10 to the said generator. The normal flow of current through this circuit is sufficient to both light the lamp 2 and cause the coil *c*⁹ to generate heat enough to expand the air in the chamber within which it is confined, thereby causing the diaphragm *c*³ to open the contacts *c*' and *c*⁸ and also open the contacts *c*' and *c*². In this way the switch C serves to automatically open the circuit of lamp 2 and at the same time automatically

open the circuit of the coil *b*⁴; also, the diaphragm *c*³ moves into engagement with the contact *c*¹¹. This results in the completion of the circuit from the generator A, through the conductors 5, 11, and 15, through the binding-post *d*⁶, through the normally closed contacts *d*⁷ and *d*⁸, which are mechanically connected, respectively, with the diaphragm *d*³ and the heating-coil *d*⁹, the latter contact being also electrically connected with said coil, and the said circuit is then continued from the said coil through the binding-post *d*¹⁰ and the conductor 16, through the lamp 3 and the conductor 17, through the binding-post *c*¹² and the contact *c*¹¹, thence through the diaphragm *c*³ and the binding-post *c*¹³, and through the conductors 18 and 10 to said generator. The normal flow of current in this circuit is also sufficient to cause the lamp 3 to glow and the coil *d*⁹ to generate heat. The heat generated by the coil *d*⁹ causes the diaphragm *d*³ to separate the normally closed contacts *d*⁷ and *d*⁸ and to also separate the normally closed contacts *d*' and *d*², it being observed that the contacts *d*' and *d*² are connected to move with the diaphragm; also, in yielding to the expansion of air at one side the diaphragm *d*³ moves into engagement with the contact *d*¹¹. This closes a circuit from the generator A, through the conductors 5, 11, through the lamp 4, through the conductor 19 and the binding-post *d*¹², through the contact *d*¹¹ and the diaphragm *d*³, and thence through the binding-post *d*¹³ and the conductors 20 and 10 to said generator. Thus the diaphragm *d*³, acting under the expansion of air caused by the heat generated at one side, opens the circuit of the lamp 3 and the coil *d*⁹ and at the same time, or immediately thereafter, closes the circuit of the lamp 4. In this way it will be seen that the normally open contacts of each switch control or are included in the circuit of the heating-coil of the next succeeding switch, whereby the second and third switches are dependent for their operation upon the operation of the previous switch; also, it will be seen that the normally open contacts of each switch control the circuit of the next lamp or group of lamps. Preferably, as illustrated, each lamp is connected in series with the heating-coil by which the lamp-circuit is automatically opened. Furthermore, as illustrated, the circuit of the first lamp and of the coil *b*⁴ includes normally closed contacts in each of the switches. In this way the first lamp cannot glow until after the last switch has been operated and has had time to cool sufficiently to allow its contacts to regain their normal condition. Consequently the lamp 1 is the first to glow, but is automatically put out by the action of the coil *b*⁴, and the other lamps then glow in succession.

It is obvious that with my improved electrical sign apparatus a sign can be provided

in which a plurality of groups of lamps can be caused to glow successively. This successive glowing of different groups of lamps in an electrical sign is designed to attract attention and is a thing so well understood that it needs no special explanation.

In Fig. 2 the arrangement is in certain respects similar to that shown in Fig. 1; but in Fig. 2 the arrangement is such that the lamps 21, 22, and 23 not only glow successively, but also even glow simultaneously. In other words, the lamp 21 glows and goes out, the lamp 22 then glows and goes out, the lamp 23 then glows and goes out, and then all three lamps glow simultaneously. The current passes from the generator E, through the conductor 24, through the heating-coil 26 of the first switch, thence through the conductor 27, through the normally closed contacts 28, 29, and 30 of the last switch, thence through the conductor 31, and through the normally closed contacts 32, 33, and 34 of the third switch. The circuit is then continued through the conductor 35 and through the normally closed contacts 36, 37, and 38 of the second switch, thence through the conductor 39 and the contact 40 of the diaphragm 41, which latter normally engage each other in the first switch, and finally through the conductors 42 and 43 to the other pole of the generator. The normal flow of current in this circuit is sufficient to cause the lamp 21 to glow and the coil 26 to generate heat. The heat generated by the said coil causes the diaphragm 41 to move away from the contact 40, thereby opening the circuit of the lamp 21, and in so doing the diaphragm also closes a circuit from the generator E, through the conductor 44 and the lamp 22, thence through the conductor 45, through the coil 46 of the second switch, through the contact 47 and the diaphragm 48 of the said second switch, through the contact 49 of said second switch, thence through the conductor 50 to the contact 51 in the first switch, through the diaphragm 41, and through the conductors 42 and 43 to the other pole of the generator. The flow of current through this last circuit is sufficient to cause the lamp 22 to glow and the coil 46 to generate heat. The heat generated by the coil 46 expands the air in its allotted chamber and causes the diaphragm to open the normally closed contacts in the circuit of the lamp 22 and the coil 46 and to also open the contacts included in the circuit of the coil 26 and the lamp 21. Also the diaphragm 48 in yielding to the pressure of the expanded air moves into contact with the two stationary contacts 52 and 53, thereby closing a circuit from the generator E, through the conductor 44, through the lamp 23, through the coil 54, through the contact 56 and the diaphragm 58, through the contact 59, through the conductor 60, through the contact 52 and the

diaphragm 48, and thence through the contact 53 and the conductors 61 and 43 to the generator. In this way current is caused to flow through the lamp 23 and also through the coil 54, thereby causing the former to glow and the latter to generate heat. The heat generated causes the diaphragm 58 to flex or bend, and thereby open the normally closed contacts in the circuit of the lamp 23 and the coil 54 and to also open the normally closed contacts provided in this switch and which are included in the circuit of the lamp 21 and the coil 26. The action of the diaphragm 58 also operates to close a circuit from the generator E, through the conductors 44 and 62, through the coil 63 of the last switch in the series, thence through the conductor 64, through the contact 65 and the diaphragm 58, through the contact 66, thence through the conductors 61 and 43 to the generator. Current flowing in this last circuit causes the coil 63 to generate considerable heat, and the heat so generated expands the air in the chamber and causes the diaphragm 67 to open the normally closed contacts 28 29 30, which latter are provided in this last switch and included, like those of the other switches, in the circuit of the lamp 21 and the coil 26. Furthermore, the diaphragm 67 in yielding to the expansion of the air at one side closes three parallel circuits through the lamps 21, 22, and 23, one from the generator through the lamp 21 and the conductor 68 to contact 69, and thence through the diaphragm 67 and the conductors 61 and 43 to the generator, another from the generator, through the conductor 44 and the lamp 22, through the conductor 70 to the contact 71, and thence through the diaphragm 67 and the conductors 61 and 43 to the generator, and the third from the generator, through the conductor 44 and the lamp 23, through the conductor 72, through the contact 73, and the said diaphragm 67, and thence to the generator through the conductors 61 and 43. Thus, as stated in Fig. 2, the arrangement is such that the lamps or groups of lamps are caused to glow successively and then to immediately all glow together or simultaneously.

In each case it will be seen that the electrothermal switches have two chambers, one at each side of the flexible diaphragm. With this construction changes of atmospheric temperature have no tendency whatever to affect the working of the switches. In other words, each switch is provided with what may be termed "counterbalancing-chambers," tending to counteract the effects of atmospheric changes in temperature. Consequently no switch can operate until heat is generated in its coil or other resistance; neither can it vary in its time or mode of operation.

It will be readily seen that the resistance of the coils or concentrating members can be

varied or adjusted to suit the requirements and conditions of any particular case. It is necessary, of course, that the second switch, for example, be capable of generating sufficient heat to effect its operation before the first switch cools sufficiently to open the thermal circuits of the said second switch, and this principle or mode of operation can be carried out or embodied in the series of switches. It will be readily understood, however, that I do not confine or limit myself to any particular form or construction of electrothermal switch. For the purposes of my invention these switches may be of any suitable, known, or approved form of construction.

What I claim as my invention is—

1. Automatic electric switch apparatus comprising a series of electrothermal switches, a translating device for each switch and connected to be operated thereby, suitable electrical supply for the said switches and translating devices, a normally closed contact at one switch in the thermal circuit of the preceding switch in the series and arranged to be opened by the operation of the said one switch, and a normally open contact at the said one switch in the thermal circuit of the succeeding switch in the series and arranged to be closed by the operation of the said one switch, for purposes substantially as described.

2. Automatic electric switch apparatus comprising a series of electrothermal switches, a translating device for each switch and connected to be operated thereby, suitable electrical supply for the said switches and translating devices, a normally closed contact at each switch, all arranged in series in the thermal circuit of the first switch of the series and each arranged to be opened by the operation of its switch, and a normally open contact at each switch except the last switch of the se-

ries, each arranged in the thermal circuit of its succeeding switch of the series and each arranged to be closed by the operation of its switch, for purposes substantially as described.

3. Automatic electric switch apparatus comprising a series of electrothermal switches, suitable translating devices connected to be operated by the switches, suitable electrical supply for the said switches and translating devices, a normally open contact at each switch except the last switch of the series, each arranged in the thermal circuit of its succeeding switch of the series and each arranged to be closed by the operation of its switch, to operate the switches in succession, and a number of normally open contacts at the last switch of the series, connected with the several translating devices and adapted to be closed by the operation of their switch to operate all of the translating devices simultaneously.

4. Automatic electric switch apparatus comprising a series of electrothermal switches, a translating device for each switch, apart therefrom and connected in the thermal circuit of its switch, suitable electrical supply for the said switches and translating devices, a normally open contact at each switch except the last switch of the series, each arranged in the thermal circuit of its succeeding switch of the series and each arranged to be closed by the operation of its switch, to operate the switches in succession, and a normally closed contact at each switch in its own thermal circuit and arranged to be opened by the operation of its switch.

Signed by me at Chicago, Cook county, Illinois, this 26th day of January, 1904.

FRANK B. COOK.
